APPARATUS FOR THE TAILORING TRADE
FOR REPRODUCING THE SHAPE OF THE
BODY OF THE CUSTOMER

Ernst Sterling, Magdeburg, Germany

Application November 14, 1929, Serial No. 407,260
In Germany August 5, 1929

4 Claims. (Cl. 223—18)

This invention relates to a tailor's dummy and consists of a framework comprising elements adjustable in all directions and a casing composed of separate members carried by said framework.

5 By adjusting the framework the casing can be adapted to the shape of any human body.

The known tailor's dummies cannot be accurately adjusted according to the shape of the body, but the tailor is always compelled to take certain measurements. This is not necessary with the dummy according to the invention, wherein the trunk can be widened, the waist lengthened, each shoulder raised or lowered separately, the shoulder width changed, the upper part inclined towards the front or rear, and the shoulders made straight or sloping.

10 Arm stumps and a neck portion are provided so that the size of the arm hole and height of the collar can be accurately set.

15 An embodiment of the invention is illustrated by way of example in the accompanying drawings in which:—

Fig. 1 is a front longitudinal section of the framework.

20 Fig. 2 is a side longitudinal section of the chest portion of the framework.

Fig. 3 is a bottom plan view of the plate of the upper frame of the framework.

25 Figs. 4 and 5 show details of the framework.

30 Fig. 6 shows a shoulder portion of the framework in side elevation.

Fig. 7 shows the means for adjusting the casing at the belly portion of the dummy.

Fig. 8 shows the dummy in side elevation.

35 Fig. 9 is an inner view of a portion of the casing.

Fig. 10 is a cross section of a portion of the casing.

40 Figs. 11 to 16 show the connection of different portions of the casing.

The trunk is formed of a casing which is carried on a framework, comprising an upper and a lower frame adapted to be separately adjusted.

45 The lower frame comprises two horizontal plates 1 and 2. The upper plate 1 has downwardly extending flaps 3 hingedly connected with flaps 3a projecting upwards from the lower plate 2. This lower frame is adapted to be supported on a stand or the like.

50 The upper frame comprises a horizontal plate 4, stays 6 and vertical rods 5.

Two vertical spindles 11 extend one at each side through the upper plate 4 and are secured in the lower plate 2 at their lower end by a screw thread 12. Each of these spindles 11 is connected by a ball joint 13 to a link 9 hingedly connected to a rack 9a extending through the plate 4. Pinions 8 mounted on spindles 13 journaled in brackets 8a on the upper side of the plate 4 engage each with one of said racks 9a.

Each of the racks 9a has a row of holes and in each of the brackets 8a a spring loaded pin is mounted and can engage in the holes in the coordinate rack and lock the same in adjusted position.

5 If one of the spindles 11 is vertically shifted by means of its screw thread 12, the plate 4 and consequently the whole of the upper frame will assume a laterally inclined position, so that one shoulder will be higher than the other. If both the spindles 11 are uniformly shifted, the plate 4 and therefore the upper frame will be inclined transversely, thereby determining the deportment of the figure.

One shoulder can also be raised or lowered by 15 disengaging the pin 14 from one of the racks and turning the coordinate pinion 8 by means of its spindle 13. If both these spindles 13 are turned uniformly, the distance between the two frames will be altered, thus varying the length 20 of the trunk.

A vertical spindle 15 is similarly mounted at the front or rear of the plate 2. This spindle also extends through the plate 1 and, as shown in Fig. 2, is connected at its upper end by a double ball joint 16, 17 to a rack 18 meshing with a pinion 19 on a spindle 13a journaled in a bracket 20 mounted on the under side of the plate 4. By rotating this spindle 13a the plate 4 and therefore the upper frame is tilted transversely.

30 The lower frame is provided with ten vertically arranged curved elements 21, each having two radially directed superposed arms 21a and 21b. Each of the upper arms 21a is slidably guided in an eye 1a on the under side of the plate 1, whereas the lower arm 21b has a pin which engages in a bifurcation on the end of one arm of a bell crank lever 22, these levers 22 being pivotally mounted on brackets 23 on the upper side of the plate 2. The other arms of these levers are hingedly connected by bolts 25 to a common screw threaded nut 24 mounted on a screw thread 26a on the lower end of a vertical spindle 26 journaled in the plates 1 and 2. 40 This screw spindle 26 has at its lower end a longitudinal bore 26b designed to accommodate a supporting pin.

45 A bevel wheel 28 is keyed on the upper end of the spindle 26 above the plate 1 and this bevel wheel meshes with a second bevel wheel 27 keyed on a horizontal spindle 29 journaled in brackets mounted on the upper side of the plate 1. If this spindle 29 is rotated, it rotates the spindle 26 through the intermediary of the 55 bevel wheels 27, 28 and thus causes the nut 24 to shift vertically on the screw thread 26a. The bell crank levers are thus caused to rock and radially shift the arms 21, thereby changing the width of the waist. The spindle 29 is divided, 60

one part having a slot and the other a tongue engaging in the slot so that the length of the spindle adapts itself to the varying width, the outer part being pulled out of the slot in the 5 other part by the casing.

It is necessary, when adjusting the dummy for a corpulent figure, to impart a greater curvature to the casing in this region than at the sides and back. Consequently the arms 21a and 21b 10 are curved as shown in Fig. 7, so that the upper end of the curved elements 21 is displaced through a greater angle than the lower end.

The upper frame plate 4 has eyes 6a in which ten rods 35 are slidably mounted and each 15 hingedly connected at its outer end to a bent lever 30 having a downwardly inclined portion 46 provided with a slot 46a. A plate 45 having ten pins 44 each engaging in the slot in one of the levers 30, is mounted on a screw thread 41 20 on the lower end of a vertical spindle 47 rotatably mounted in the plate 4 guided on the rods 5, so that, when this spindle 47 is rotated, the plate 45 is caused to move vertically, thereby radially shifting the rods 35 through the intermediary of the levers 30. Two adjacent levers 25 30 on each side of the upper frame are connected to a shoulder piece, comprising two hingedly interconnected members 31a and 31b (Fig. 6). The member 31a of each shoulder piece has a curved arm 39 projecting outwardly and downwardly into the medial vertical plane between the members 31a and 31b. This arm has at its lower end an eye 64 adapted to receive an arm member not shown in the drawings.

Where the levers 35 are shifted, they will also 35 displace the shoulder pieces 31 laterally, thereby adjusting the width across the shoulders.

On the upper end of the rods 5 a plate 49 is 40 slidably mounted. This plate carries a hollow spindle 48 having a screw thread 48a at its lower end engaging in a screw threaded disc 48b fixed on the rods 5 so that, if the hollow spindle 48 is rotated, it will shift vertically in the disc 48b. Vertical rods 34 are hingedly connected at their 45 upper end to the disc 48 by means of a wire 50 extending through the rods 34 and surrounding the disc 49 in a horizontal groove 52. These rods 34 will therefore participate in the vertical movement of the spindle 48. Shoulder rods each comprising a rod 32 having straps in which a second rod 33 is longitudinally slidably, are hingedly connected at one end to one of the shoulder pieces 31 and at the other end to one of the neck rods 34 so that, when the disc 49 is vertically shifted, the 50 shoulder rods 34 will swing on the shoulder pieces 31 and determine the inclination of the shoulders. Owing to the rods 32 and 33 being mutually slid- 55 able, the length of the shoulder rod can adapt itself to the inclination.

Each of the vertical rods 34 has near its lower 60 end two outwardly projecting eyes 34a arranged at a distance apart, and in which a guide rod 37 is slidable. To each of the rods 37 a connecting rod 43 is hingedly connected at one end between the eyes 34a on its coordinate rod 34 and at the other end has a lug 43a engaging a screw spindle 42 rotatably mounted in a bracket 41 mounted on the arm 31a of the shoulder piece 31. If this spindle 42 is rotated, its shoulder piece 31 will be 65 shifted laterally, thereby adjusting the width between the shoulders.

When the shoulder piece 31 moves outwards its rod 35 must also move outwards causing the neck rod 34 connected to the rod 35 through the intermediary of the guide rod 37, to swing about its

wire 50. One of the levers 30 is, however, also hingedly connected to this rod 35 so that this lever 30 must likewise move outwards and will swing upwards at its inner end under the action of the pin 44 on the plate 45 engaging in the slot 46a in the inclined portion 46 of this lever 30. 5

The rods 37 are each connected at their lower end to the inner end of one of the rods 35 carrying a shoulder piece so that, when these rods are horizontally shifted, they will also cause the rods 37 to 10 swing around the wire ring 52, thereby automatically adjusting the size of the neck according to the width between the shoulders. As moreover the shoulder bars 32, 33 are connected to the vertical rods 34, their position to the horizontal will 15 also be automatically adjusted.

The remaining levers 30 at the front and rear of the upper frame are each connected to one end of a telescopic neck rod 30a which is hingedly connected at its other end to the wire ring 52 in 20 the plate 49 (Fig. 2). Thus, when the plate 45 is vertically shifted, these rods 30a like the rods 34 are also swung on the wire ring 52 so that these rods 30a and the rods 34 adjust the size of the neck. 25

The whole of the framework is enclosed by a casing composed of a large number of mutually displaceable elements 83 to 95 of different shapes as shown in Figs. 8 to 16. These elements are connected to the framework by holders (Fig. 13) 30 which engage square headed screws 85 projecting from the parts 21, 30, 30a, 32, 33, 34 and 39 of the framework. These screws have a square head and a slightly thinner neck. On this slightly thinner neck, serving for accommodating the casing 35 holders, discs 85c and 85d are mounted. Between these discs a spiral spring is arranged, bearing against the disc 85d and pressing the disc 85c against the casing holders, so that, when the screw 85 is moved, the disc 85c is forced to yield 40 slightly, in order to avoid bending and not to cause any hindrance. The disc 85d is rigidly connected with the shank of the screw 85 by a pin 85e. The shank has a screw thread.

The casing holders may be of very different 45 shapes. As the casing parts are moved apart, when the trunk is widened, so that gaps are formed between them, the holders 93 to 90 (Figs. 9 to 16) must be slotted and of different length. The screw 85 is passed through the slot. The 50 holders 98 are pivotally connected with the casing parts. Holders 96, the casing parts of which are carried along by the bows, are rigidly connected with the casing parts and have only a hole in which the screw 85 rotatably engages. The individual holders must not hamper one another. They must therefore be set off so that they can 55 pass the one along the other. These are shown in Fig. 9. How the set off portions are carried out is to be determined from case to case. 60

A number of casing parts in the waist region must mutually guide one another. The casing of the waist-region, the rear side of which is shown in Fig. 9, consists of trapeziformed parts 86 to 89. Some of these trapeziformed parts are 65 further subdivided and held together by hinges. At the subdivided portions the parts 86 to 89 are of four cornered shape. The subdividing of this triangle at 90 and 91 is necessary, owing to the different body shapes. 70

In order to reproduce these shapes, the hinge is adjustable.

The parts 88a are rigidly connected with a rigid flap 101. The parts 88 are rigidly connected with a flap 102. The flaps 101 and 102 75

are hinged together. A screw 103 is guided by and mounted in the flap 102, the shank of said screw engaging in the nut part 104 of the flap 101. The shape of the casing is altered by the 5 turning of the adjusting screw 103, which bends outwards or inwards the casing parts.

The casing part 87a is mounted by the holder 96 on the adjusting screw 85a by which it is carried along at every movement. The casing part 10 88a is also mounted on the screw 85 and carried along thereby. In the case of a lengthening of the waist the trunk parts move apart and carry the casing part 88a in upward direction, whereas the case part 87a is moved in downward direction. The narrow end of the part 15 87 is moved along the part 88 and held in a certain position by a holder 106, sliding up and down on a wire 105 of the part 88. The narrow end of the part 88 is guided on the part 20 87 in a similar manner, so that a mutual guiding is obtained. For this reason it is possible to carry out an alteration in the length of waist without horizontal gaps being formed.

In the case of a widening of the trunk the 25 casing parts 87a and 87 (Fig. 10) are also guided along by the screw 85a through the holder 96 following the movements of the bow 21. The narrow ends of the casing parts 87 and 88 are held in vertical and horizontal position on the 30 wires 105 in the manner above described, so that the third fastening end of the part 87a must yield to the movements of the parts 87 and 88, caused by the holder 98 rotatably mounted on the casing parts and holding together the 35 end of the casing parts only in the plane position with regard to casing parts, the screw 85b sliding along in the slots 107 of the holders 98, because all the casing parts move away from the screw 85b. The parts 86 and 89 also make 40 this movement. The narrow end of the part 89 is guided by the holder 97 that slides in bearings of the casing part 89.

The holder 100 on the other hand is rigidly connected with the casing part 86 and slides 45 along the screw. The casing parts 90 are guided along by the holder 96, and held by the holders 99 in height and width position and by the holder 98 at the third corner in the height position.

I claim:

50 1. A tailor's dummy, comprising in combination a casing composed of a plurality of mutually displaceable elements of different shapes, holders connecting said elements, a framework in said casing and composed of an upper frame at the chest portion of the dummy and a lower frame at the belly portion of the dummy, each of said frames comprising a plate, a plurality of members radially shiftable relative to said plate, a common central element, levers connecting each of said members to said central element, means projecting from said members and connected to said holders, and a vertical spindle engaging said central element and adapted to be rotated to vertically displace said central element to radially shift said members through the intermediary of said levers to vary the girth of said casing at the chest and belly portions of the dummy respectively, and means for mutually displacing said frames in vertical direction to adjust the length of said casing.

55 2. In a tailor's dummy a chest framework, comprising in combination a stationary plate, two parallel vertical rods extending through and fixed in said plate, a screw threaded disc rigidly mounted on said vertical rods, a disc slidably on said

rods and having an annular groove in its circumference, a hollow spindle rotatably mounted in said slidable disc and having a screw thread at its lower end engaging said screw threaded disc, a wire ring in the groove of said slidable disc, a plurality of neck rods pivotally mounted at one end to said wire ring at the front and back of the dummy, slotted levers connected to the other end of said neck bars, a vertical spindle extending through said hollow spindle and rotatably mounted in said plate between said vertical rods, said vertical spindle having a screw thread at its lower end, a plate having a central screw threaded hole engaging said screw thread and adapted to be vertically shifted by said vertical spindle, pins projecting from the periphery of said last mentioned plate, each engaging in the slot of one of said levers to rock said levers and swing said neck rods on said slidable ring to adjust the size of the neck, lateral vertical rods pivotally mounted on said slidable disc, a telescopic shoulder bar connected at one end to each of said rods, two shoulder pieces one hingedly mounted on the other end of each of said shoulder bars, slotted levers one connected to the lower end of each of said shoulder pieces and engaging with its slot the pins projecting at the sides of said shiftable plate, said last mentioned levers adapted to swing said shoulder pieces outwards on said shoulder bars during the displacement of said shiftable 30 plate, guide rods radially shiftable on the under side of said stationary plate and each connected at one end to one of said last mentioned levers, vertical rods extending through said stationary plate and each slidably connected to one of said lateral pivotally mounted rods and adapted to transmit the movement of said last mentioned levers to said lateral rods through the intermediary of said guide rods to vary the inclination of said shoulder bars to the horizontal, and means 35 connected to each of said last mentioned vertical rods and to each of said shoulder pieces adapted to laterally shift between said shoulder pieces and determine the length of said telescopic shoulder bars.

40 3. In a tailor's dummy a belly framework, comprising in combination two superposed stationary plates, guides on the under side of the upper of said plates, horizontal bars shiftable in said guides radially to said upper plate, vertical curved elements one on the outer end of each of said horizontal bars, bell-crank levers pivotally mounted on the upper side of the lower of said plates, arms inwardly projecting from said curved elements and each hingedly connected to one arm of one 45 of said bell crank levers, a common screw nut connected to the other arm of all of said bell crank levers, a vertical spindle journaled in said superposed plates and having a screw thread engaging said nut, and means for rotating said 50 spindle to vertically displace said nut and radially shift said curved elements through the intermediary of said bell crank levers.

45 4. In a tailor's dummy the combination of an adjustable framework with a movable chest portion composed of adjustable elements, a casing carried by said adjustable elements composed of small triangular elements, holders for said triangular elements, adjusting screws connecting said triangular elements to said holders, wires and adjustable hinges on several of said casing elements adapted to mutually support one another.
